Patented Nov. 7, 1922.

UNITED STATES PATENT OFFICE.

GEORGE ALBERT TUCK, OF SAN FRANCISCO, CALIFORNIA.

VALVE AND ACTUATING MEANS.

Application filed April 4, 1921. Serial No. 458,268.

To all whom it may concern:

Be it known that I, GEORGE ALBERT TUCK, a citizen of the United States, residing at San Francisco, in the county of San Francisco and State of California, have invented 5 certain new and useful Improvements in Valves and Actuating Means; and I do declare the following to be a full, clear, and exact description of the invention, such as 10 will enable others skilled in the art to which it appertains to make and use the same.

This invention relates to an improved valve and actuating means and one object of the invention is to provide a valve of the 15 double seat type having the stem movable to bring the head into and out of engagement with the valve seat so that the valve may be closed or left open and prevented from leaking around the stem when in an 20 open position.

Another object of the invention is to provide improved operating means for the valve, this means being so constructed that the valve may be given initial movement by 25 electrically operated means, and movement of the valve to an adjusted position completed by spring operated means serving not only to give the additional movement to the valve stem but also serving to retain 30 the stem in the adjusted position.

Another object of the invention is to so construct this operating means as to include a plunger which is connected with the valve stem and extends through solenoids 35 and is provided with a section forming an armature for the solenoids and also carries sections for bridging space between spaced contact elements of the solenoids, the circuit closing elements of the plunger being 40 spaced apart a sufficient distance to permit one to be in an operative or circuit closing position with the second in an inoperative position.

Another object of the invention is to so 45 construct this valve operating device that a three-wire system may be used for selectively energizing the solenoids, the circuit through the energized solenoids being broken and the space between the spaced 50 contacts of the second solenoid bridged so that the second solenoid will be ready for operation after the valve has been moved to an adjusted position.

Another object of the invention is to so 55 construct the device that the spring oper-

ated means for moving the plunger and holding the same in an adjusted position will be very effective in operation and will prevent the plunger from accidentally moving out of the adjusted position. 60

This invention is illustrated in the accompanying drawings, wherein:

Figure 1 is a vertical sectional view through the valve and operating means.

Figure 2 is a transverse sectional view 65 taken along the line 2-2 of Fig. 1.

Figure 3 is a fragmentary sectional view showing the wiring of the solenoids in diagram.

This valve operating means is used in connection with a valve having a body 1 open at its ends and provided with a partition 2 having a valve seat 3 for engagement by the head 4 of the valve when in a closed position. This head is carried by a stem 70 6 and when in an open position seats in the valve seat 7 at the lower end of the passage through the neck 8 of the body so that a tight closure will be provided about the stem and thus leakage prevented through 75 the neck about the stem.

The operating means is provided with a cylindrical casing 9 having a cap 10 at its upper end and a head 11 at its lower end, the head 11 being connected with the neck 80 8 of the valve body and provided with an opening so that the valve stem 6 may extend 85 up into the casing. Within the casing there has been provided partitions 12, 13, 14 and 15 which are formed of fibre or any other 90 suitable insulating material, the partitions 13 and 14 being provided with openings so that the metal tube 16 may be mounted to extend longitudinally of the casing between the partitions 13 and 14. This tube provides 95 a core for the solenoids 17 and 18 and these partitions carry spaced contact strips 19, 20, 21 and 22. From an inspection of Fig. 3, it will be seen that a three-wire circuit 100 is used in connection with the solenoids and includes a battery 23 having a wire 24 leading therefrom and connected with a movable switch element 25 which may be brought into engagement with the terminal contact points 26 and 27 carried by the line wires 28 and 105 29. The wire 29 extends into the casing through the partition 12 and is connected with the contact strip 20 and the wire 28 extends into the casing and is carried downwardly through the partitions 12, 13 and 14 110

and is connected with the contact strip 22. A line wire 30 leads from the battery into the casing and after being passed through the partition 12 is carried through the partition 13 and connected with the windings of the two solenoids 17 and 18, the opposite terminal of the solenoids being connected with the contact strips 19 and 21. It will thus be seen that by means of this wiring, one solenoid may be energized without the second being energized.

A plunger 31 which is formed of fibre or some other suitable insulating material is slidably mounted for movement longitudinally in the casing and extends through the tube 16 and through openings formed in the partitions 12 and 15 and has its lower end portion connected with the valve stem 6 by means of a coupling 32. The lower portion of the casing is provided with openings 33 so that ready access may be had to the coupling in order to permit of adjustment. This plunger is provided with an elongated metal sleeve 34 which is positioned in the tube 16 intermediate the length of the same and will constitute an armature for the two solenoids thus permitting the plunger to be moved longitudinally when either of the solenoids has been energized. Smaller sleeves 35 and 36 which are also formed of brass or other suitable metal are carried by the plunger and provide circuit closing means or elements for fitting between the spaced contact elements of the solenoids and thus permitting current to pass to the solenoids. It should be noted that the distance between the circuit closing elements 35 and 36 is greater than the distance between the contact elements carried by the partition 13 and the contact elements carried by the partition 14. Therefore, if the circuit closing element 35 is in an operative position between the contact strips 19 and 20, the circuit closing element 36 will be positioned beneath and out of engagement with the contact strips 21 and 22. In the same way, if the sleeve 36 is bridging the space between the contacts 21 and 22, the sleeve 35 will be positioned above the contact strips 19 and 20.

When this device is in use, it is desired to have the plunger given initial movement by one of the solenoids and the movement continued by spring operated means which in addition to completing movement of the plunger will serve as means to releasably hold the plunger in an adjusted position. Therefore, the partition 12 has been provided with standards 37 between which the plunger passes. Lever arms 38 are pivotally connected with the standards 37 upon pins 39. Pins 40 are provided at the outer ends of the levers and adjacent their inner ends, the levers have been provided with longitudinally extending slots 41 to receive the end portions of a pin 42 carried by the plun-

ger. Springs 43 are connected with the end portions of the pins 40 and will normally serve to draw the outer end portions of the levers inwardly or in other words toward each other. Therefore, when the device is 70 in use and the switch arm 25 moves to energize one of the solenoids, the solenoids will act through the armature 34 to draw the plunger longitudinally and in doing so, the levers will be swung upon their pivots until 75 they pass a dead center. During this movement, the springs will be stretched by movement of the levers. After passing the dead centers, the springs will act upon the levers, to draw the outer end portions thereof toward each other and the plunger will be given additional longitudinal movement through the action of the springs and levers to such an extent that the valve will be moved to either an open or a closed position and the circuit closing element for the energized solenoid moved to an operative position and the circuit closing element for the solenoid which is not energized moved to an operative position. The spring will retain the plunger valve in the adjusted position. By this means, the passage of current through the solenoid which was originally energized will be cut off and waste of current prevented and further the solenoids 80 85 90 95 100 105 110 115 120 125 130 prevented from being worn out by becoming overheated. When it is desired to change the position of the valve and return it to the original position, it is simply necessary to swing the switch arm 25 to engage the second contact and the second solenoid will be energized thus repeating the operation as already described above. It will thus be seen that there has been provided a valve operating device which is very effective in operation and includes electrically energized means and also spring operated means completing movement started by the electrically operated means and further serving to releasably but securely hold the valve in an adjusted position.

I claim:

1. The combination with a valve including a sliding stem, of operating means comprising a casing, a plunger slidably longitudinally in the casing and releasably connected with the valve stem, electrically operated means in the casing for moving the plunger when energized and including spaced contacts, circuit closing means carried by the plunger in spaced relation to each other for engaging the spaced contacts with one of the circuit closing means in an operative position when the other is in an inoperative position, and other means for moving the plunger longitudinally and holding the plunger in a set position with an energized circuit broken after the electrically operated means has been energized to impart initial movement to the plunger.

2. The combination with a valve including a sliding stem, of operating means comprising a casing, superimposed solenoids in the casing each having spaced contacts, a plunger extending through the solenoids and having a section forming an armature for the solenoids, circuit closing means carried by the plunger and spaced apart a greater distance than the space between the contacts of one solenoid and the contacts of the second solenoid, and spring actuated means for imparting additional movement to the plunger and retaining the same in an adjusted position with the circuit closing element for the solenoid energized and giving initial movement to the plunger in an inoperative position.
3. The combination with a valve including a sliding stem, of operating means comprising a casing, superimposed solenoids in said casing, a plunger slideable in said casing through the solenoids and formed of insulating material and connected with the valve stem, a collar carried by the plunger and forming an armature for the solenoids, spaced contacts above and below the solenoids forming elements of a circuit for selectively energizing the solenoids, circuit closing elements carried by the plunger and spaced a distance to place one element in engagement with its spaced contacts when the second element is out of engagement with its spaced contacts, and spring operated means for moving the plunger longitudinally after initial movement thereof by one of the solenoids, movement of the plunger moving the circuit closing element from between the spaced contacts of the energized solenoid.
4. The combination with a valve including a sliding stem, of operating means for the valve comprising a casing, partitions of insulating material in the casing, a tube carried by the partitions and extending longitudinally of the casing between the partitions and forming a solenoid core, a plunger slideable longitudinally of the casing and passing through the tube and having one end portion connected with the valve stem, an element carried by the plunger within the tube and constituting an armature, solenoid windings upon the tube between the partitions to provide superimposed solenoids, a circuit for the solenoids including contact strips carried by each partition, and circuit closing elements carried by the plunger for extending between and bridging the space between the spaced contact elements of the partitions, and spring operated means having connection with the plunger for imparting movement to the same and hold the plunger in an adjusted position with the circuit closing element for one set of spaced contacts in an operative position and the circuit closing element for the second set of spaced contacts in an inoperative position.
5. The combination with a valve including a sliding stem, of operating means including a casing, a plunger slideably mounted in the casing and having connection with the valve stem, electrically operated means for initially moving the stem to adjust the valve, and spring actuated means for completing movement of the stem and rendering the electrically operated means inoperative, said spring actuated means comprising levers pivotally mounted upon opposite sides of said plunger and having their inner end portions slidably and pivotally connected with the plunger, and spring means connected with the outer end portions of the levers to normally draw the outer end portions of the levers toward each other.

In testimony whereof I have hereunto set my hand.

GEORGE ALBERT TUCK.
